United States Patent Office

Des. 225,742
Patented Jan. 2, 1973

225,742

DATA KEYBOARD CONSOLE

John Davis Sims, Cary, N.C., assignor to International
Business Machines Corporation, Armonk, N.Y.
Filed Aug. 27, 1971, Ser. No. 175,811
Term of patent 14 years
Int. Cl. D14—02

U.S. Cl. D26—5

FIG. 1

FIG. 2

FIG. 3

FIG. 4

FIG. 5

FIG. 6

FIG. 1 is a perspective view taken from the front and right side of a data keyboard console embodying my new design;

FIG. 2 is a perspective view taken from the rear and right side thereof;

FIG. 3 is a top plan view thereof;

FIG. 4 is a bottom view thereof;

FIG. 5 is a rear elevational view thereof; and

FIG. 6 is a right side elevational view.

I claim:

The ornamental design for a data keyboard console, as shown.
